(57) **CLAIM**

The ornamental design for a lightning protection mount, as shown and described.

DESCRIPTION

FIG. 1 is a front perspective view of a lightning protection mount in accordance with the invention;

FIG. 2 is a rear perspective view thereof;

FIG. 3 is a partially cut away rear perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left side elevation view thereof;

FIG. 9 is a right side elevation view thereof;

FIG. 10 is an exploded environmental perspective view of the lightning protection mount in accordance with the invention; and,

FIG. 11 is an exploded environmental perspective view of the lightning protection mount in accordance with the invention.

The stippling shown in FIGS. 2, 3, 5, 10 and 11 represents a polymeric material surface.

The broken lines shown in FIGS. 10 and 11 represents the environment of the claimed design and forms no part thereof.

1 Claim, 4 Drawing Sheets

Related U.S. Application Data

continuation-in-part of application No. 14/600,270, filed on Jan. 20, 2015, which is a continuation of application No. 13/676,292, filed on Nov. 14, 2012, now Pat. No. 8,950,055.
